DESIGN FOR A SHOE SOLE

Sam Incardona, Waco, Tex.

Application October 30, 1943, Serial No. 111,540

Term of patent 14 years

To all whom it may concern:

Be it known that I, Sam Incardona, a citizen of the United States, residing at Waco, in the county of McLennan and State of Texas, have invented a new, original, and ornamental Design for a Shoe Sole, of which the following is a specification, reference being had therein to the accompanying drawing, forming a part thereof, in which:

I claim:

The ornamental design for a shoe sole, as shown and described.

SAM INCARDONA.
